(57) **CLAIM**

The ornamental design for a drawer guide bracket, as shown and described.

DESCRIPTION

FIG. 1 is a rear, top, right side perspective view of a drawer guide bracket embodying my design;
FIG. 2 is a rear elevational view thereof;
FIG. 3 is a bottom plan view thereof;
FIG. 4 is a top plan view thereof;
FIG. 5 is a right side elevational view, the left side being a mirror image thereof;
FIG. 6 is a front elevational view thereof;
FIG. 7 is a cross-sectional view along lines 7—7 of FIG. 2; and,
FIG. 8 is a cross-sectional view along lines 8—8 of FIG. 2.
